UNITED STATES PATENT OFFICE.

ULYSSES G. LEE, OF CHICAGO, ILLINOIS.

SCREEN FOR Portholes AND THE LIKE.

1,336,038.

Specification of Letters Patent.

Patented Apr. 6, 1920.

Application filed August 5, 1919. Serial No. 315,512.

To all whom it may concern:

Be it known that I, ULYSSES G. LEE, a citizen of the United States, and resident of Chicago, Illinois, have invented certain new 5 and useful Improvements in Screens for Portholes and the like, of which the following is a specification.

It is an object of the invention to provide screens for circular openings or windows 10 such as the port holes of vessels and the invention consists in the features and combination of parts hereinafter described and particularly pointed out in the claims.

In the accompanying drawings:

15 Figure 1 represents a side elevation of the screen and frame in its unset condition ready to be placed in the port hole or circular window opening to be locked therein.

Fig. 1^a is a view similar to Fig. 1 but only 20 showing a portion of the screen and frame, the parts being in their unset position or in other words in their unexpanded condition.

Fig. 2 is a view similar to Fig. 1 but only 25 showing a portion of the screen and frame, the parts being in their set position or in other words in their expanded condition to be held within the circular opening or port hole.

Fig. 3 is a perspective view of the end 30 portions of the clamping ring or strip.

Fig. 4 is a perspective view of a bridge member which bridges the gap in the clamp member.

Fig. 5 is a perspective view of the operating member.

Fig. 6 is a cross sectional view of the main frame member with a portion of the screen in position and the clamping ring or strip.

Fig. 7 is a perspective view of a modification of one end of the clamping ring or strip.

In these drawings the screen material is indicated by 1 this being of circular form having an edge portion 2 extending from the main portion at right angles thereto as 45 shown in Fig. 6. The screen material may be of ordinary wire netting and its flanged or rim portion 2 is seated within a main frame member or ring 3 which is of channeled form being provided with inturned 50 flanges 4 and 5. The screen material is held within the main frame member 3 by a clamping ring 6. The main frame member is divided at 7 and the clamping ring 6 is also divided, one of its ends being turned to 55 form an eye 8 receiving the pivot pin of a toggle or operating lever 9 to which is con-

nected at the opening 10 a spring member 11 which at its other end engages the inwardly turned portion 12 on the other end of the clamping strip or ring that is opposite the end at which the eye 8 is formed. The spring member is of spiral form and it constitutes in effect one arm of a toggle lever arrangement of which the operating lever or arm 9 forms the other member, for 60 it will be observed by reference to Fig. 1 that the point of connection 10 between the spring 11 and the lever 9, is below or to one side of the pivot eye 8.

With the parts in the position shown in 70 Fig. 1 the screen may be said to be in its collapsed or unexpanded condition, its diameter then being such that it readily can be placed in position within the circular window opening or port hole, whereupon by 75 moving the lever 9 toward the right in Fig. 1 to the position shown in Fig. 2 the binding or clamping strip 6 will be expanded, because its two ends will be moved farther apart from each other than in the relation 80 of Fig. 1 and the pressure thus exerted through this expanding strip or ring will expand the main frame member 3 by forcing its ends farther apart and then the main frame member will be clamped against the 85 wall of the window opening to be held securely in place. The clamped position of the parts is shown in Fig. 2 and it will be noticed that the point 10 where the toggle spring connects with the finger lever 9 will 90 have crossed the line connecting the pivot eye 8 with the point where the toggle spring bears upon the end 12 of the clamping strip or ring. The expansion of the clamping strip is due to the combined action of the 95 toggle lever 9 and the toggle spring 11 forcing the ends of the split ring apart. The presence of the spring 11 will permit the screen frame to accommodate itself to different diameters of circular window openings or port holes within certain limits because the spring will yield after the main split frame 3 has been finally seated against the wall of the window opening. This 100 spring will allow for expansion and contraction of the screen frame and the screen material.

In order to bridge the space between the ends of the clamping strip I provide a bridge plate 13 Fig. 4 provided with an 110 opening 14 to engage a stud 15 on the end of the clamping strip or ring, the said plate

13 being sufficiently long as shown in dotted line in Fig. 1 to extend across the gap between the ends of the clamping ring and to overlap the end at which the eye 8 is located.

- 5 In order to provide a flush surface to bear upon the rim or flange 2 of the screen material I form shoulders 16 and 17 on the clamping strip near its ends so that the extreme ends of the strip will lie in a lower plane 10 than the main portions of the strip and this provides the necessary space for receiving the ends of the bridge plate 13 the outer surface of which will then form substantially a continuation of the outer surface of the 15 clamping strip, being throughout at substantially the same distance from the center of the screen material so that an unbroken bearing surface will be provided to engage the inner side of the rim 2 of the 20 screen material.

Instead of employing a bridge member shown in Fig. 4 of a separate piece from the clamping ring I may as shown in Fig. 7 provide an extension 18 on the clamping 25 ring which will project sufficiently far beyond the downturned lug 19 to bridge the space between this end of the clamping strip and the other end to which the toggle lever is pivoted. In this form the lug 19 30 which is cut out from and bent down in relation to the strip forms the fulcrum or bearing which is engaged by the end of the spring 11.

It will be seen that the whole device is 35 self contained and may be marketed and handled in applying or removing as one body. It will suit different sizes of window openings and will allow for expansion and contraction.

40 The end of the lugs 12 and 19 are rounded in order not to catch in the screen material, and the end of the extension 18 is thinned.

I do not limit myself to the particular 45 construction shown, and as one modification I may employ a plurality of the toggle arrangements, these being disposed at different points around the circumference of the ring. By employing a number of toggles it will be possible to get more expansion 50 and contraction of the frame in setting it in position or removing it therefrom. The expansion of the device is limited by the screen cloth only which can be expanded 55 about one-half inch in one place, but with a number of toggles the expansion can be increased.

What I claim is:

1. A screen for circular window openings 60 or port holes comprising an expandable substantially circular frame carrying the screen material together with means for securing the frame in place in said opening.

2. In combination in a screen for port 65 holes and like window openings, an expansi-

ble frame member of substantially circular form, screen material carried thereby and means for expanding the circular frame to thereby hold it within the said opening.

3. In combination a substantially circular 70 expandable frame member, screen material carried thereby, and resilient means for expanding the said frame member against the wall of the window opening to be held by frictional engagement therewith, substantially as described.

4. In combination a split expandable frame member of substantially circular form, screen material carried thereby and means for expanding the split ring to seat 80 it in the window opening.

5. In combination a substantially circular expandable frame member, screen material carried thereby and toggle means including a spring for expanding the frame member 85 against the wall of the window opening, substantially as described.

6. In combination a substantially circular expandable frame member, screen material, an expandable substantially circular clamping member to clamp the screen to the frame member and means for expanding the clamping member to hold the screen and through the expansion of said member to expand the frame member into holding 95 contact with the wall of the window opening, substantially as described.

7. In combination, a split expandable frame ring, a split expandable clamping ring, screen material clamped to the frame 100 ring by the clamping ring and toggle means between the ends of the clamping ring to expand the same to clamp the screen material against the frame ring and to expand the latter against the wall of the window opening, substantially as described.

8. In combination, a split expandable frame ring, a split expandable clamping ring, screen material clamped to the frame 110 ring by the clamping ring and toggle means between the ends of the clamping ring to expand the same to clamp the screen material against the frame ring and to expand the latter against the wall of the window opening, said toggle means being yieldable 115 to accommodate different sizes of window openings and to allow for expansion and contraction, substantially as described.

9. In combination a split expandable frame member of substantially circular 120 form, screen material having a rim portion extending at right angles to its body portion and bearing against the inner side of the frame member an expandable split clamping ring bearing on the rim of the 125 screen material and holding it against the frame member and means for expanding the clamping ring, substantially as described.

10. In combination a split expandable 130

frame ring of channeled form, screen material having a rim portion extending at right angles to its body portion and seated in said channel, a split clamping ring also seated against the said rim portion, and means for expanding the clamping ring and through it expanding the frame ring, substantially as described.

11. In combination, screen material, a split expandible ring member, a toggle arm pivotally mounted and a spring connected with the toggle arm and connected with the end of the expandible ring, substantially as described.
- 10 12. In combination a frame member split and expandible, a clamping ring split and

expandible, screen material held by said members, and a bridge piece extending over the split portion of the clamping ring, substantially as described.

20

13. In combination a split expandible frame member, a split expandible clamping ring having an inturned lug, a toggle arm pivoted to one end of the split ring, a spring connected to the toggle arm and connected to the inturned lug and screen material held between the rings, substantially as described.

In testimony whereof, I affix my signature.

ULYSSES G. LEE.
